Specification for Design.

Patented June 28, 1921.

Application filed March 17, 1921. Serial No. 453,154. Term of patent 14 years.

To all whom it may concern:

Be it known that I, FRED M. EMBANKS, a citizen of the United States, residing at Cleveland, in the county of Cuyahoga and State of Ohio, have invented a new, original, and ornamental Design for Railroad-Spikes, of which the following is a specification, reference being had to the accompanying drawing, forming part thereof.

Figures 1 and 2 are side and front views respectively, showing my new design for a railroad spike.

I claim:

The ornamental design for a railroad spike, as shown.

FRED M. EMBANKS.
